UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

AUXILIARY CARD-FEED.

1,282,626.

Specification of Letters Patent. Patented Oct. 22, 1918.

Application filed June 14, 1915. Serial No. 33,863.

To all whom it may concern:

Be it known that I, JAMES POWERS, a citizen of the United States, residing in New York, in the county of New York and State 5 of New York, have invented certain new and useful Improvements in Auxiliary Card-Feeds, of which the following is a specification.

This invention relates to feeds for card 10 manipulating machines which feeds properly direct and position the cards that have been discharged from such machines, and relates especially to feeds for properly directing and positioning cards that have been 15 discharged from a sorting machine.

One of the main objects of the present invention is to provide an auxiliary card feed for so directing the cards after having been passed through a sorting machine that 20 they will be arranged in proper order in the compartments into which they are fed.

As a matter of convenience, it is desirable to arrange a plurality of compartments in tiers, each tier containing a number of compartments 25 one disposed above the other into which the cards are discharged according to their data. When being discharged into these compartments, the cards are guided to their position by deflectors. It has been 30 found in actual practice that when the cards are rapidly discharged by feeding rolls, they will acquire a static charge of electricity due to which, when the cards are introduced into their respective compartments, they will 35 readily cling to one of the side walls until their electricity is discharged. Consequently if a second card is fed into such compartment before the first one has separated from the side wall, such second card 40 will drop onto the pile out of its order. To overcome this defect so that such intersorting will be absolutely prevented is another main object of the present invention.

To this end, a system of revolving rolls 45 or cones is arranged and operated in each of the compartments upon which the cards are discharged from the sorting machine and which revolving cones in turn direct the cards to their final position in an orderly pile.

It is still another object of the present invention to provide such a construction of a compartment in which the finally sorted pack of cards can be quickly and easily removed 55 from such compartment.

These and other features, capabilities and advantages of the invention will appear from the subjoined detail description of one specific embodiment thereof illustrated in the accompanying drawings in which—

Figure 1 is an elevation showing one side 60 of a sorting machine and the attached tiers of compartments, and also showing the system of levers whereby the initial deflectors of the several compartments are actuated.

Fig. 2 is an elevation showing the other side of such machine with the attached tiers of compartments, on which side the compartments are partially open showing the revolving cones.

Fig. 3 is an enlarged fragmental view 70 partly in section along the line 3—3 of Fig. 2 looking in the direction of the arrows.

Fig. 4 is a fragmental view partly in section along the line 4—4 of Fig. 3 showing 75 a side view of the cones.

Fig. 5 is a fragmental view partly in section along the line 5—5 of Fig. 3 showing a plan view of the cones.

Fig. 6 is an axial section of one of the 80 cones which is mounted on an idle shaft.

Fig. 7 is an axial section of one of the cones which is mounted on the driving shaft.

Fig. 8 is a diagrammatic view illustrating 85 one complete passage of a card.

In the embodiment shown, there is provided a main frame 10 to one side of which (the left side of Fig. 1) at its upper end there is provided a bracket 11 on which a card hopper 12 is mounted, the hopper 12 having a reciprocating slide 13 forming the floor member of the hopper on which the cards C are supported and by means of which slide 13 the cards are fed to the feed rolls 14, the slide being connected by a suitable lever 15 to a cam link 16 pivoted at one end on the stud 17 and actuated by a cam 18 mounted on the main driving shaft 19.

By means of the feed rolls 14, each card is passed between the plates 20 and 21 of the 100 card analyzing mechanism 22 whereupon the pins 23 are actuated in accordance with the system forming the subject matter of my copending application, Serial No. 677,771, filed February 15, 1912, to analyze the card, 105 whereupon such of the pins 23 as have found perforations actuate suitable leverage not shown to release a locking bar 24 which will permit its opposing rods 25 to be actuated which in turn will set a deflector 26 in posi-

tion to deflect the card being sorted. The arrangement as fully described in my co-pending application is such that each deflector 26 is operatively connected with one of the pins 23 so that whenever a certain pin 23 is actuated, its thereto-connected deflector 26 will be set and permit the card being sorted to be discharged into the compartment at the entrance of which such deflector 26 is located, the deflector being maintained in such set position until after the card being sorted is discharged from between the plates 20 and 21 and advanced by suitable feed rolls to such deflectors 26, the deflectors 26 when set extending into such path of movement of the discharged cards.

After a card has been deflected into a compartment, a restoring mechanism is operated comprising the vertically extending bar 27 (Fig. 1) connected by the link 28 with suitable actuating mechanism not shown whereby the deflector 26 that has been actuated, will be restored to non-deflecting position.

The compartments are arranged in a plurality of tiers A, B, C, D, etc., one adjacent to the other formed by a plurality of parallel walls 29 and a plurality of end walls 30 secured to such parallel walls at one end thereof and closing one end of the tiers formed by such parallel walls, the other end of the tiers being open to permit the removal of the cards from such end. Each tier with the exception of the first one adjacent to the card analyzing mechanism is divided into two compartments 31 and 32, the lower compartment 32 having a floor member 33 which is inclined at a double angle, in other words, extends downwardly from its end wall 30 toward the open side of the compartment 40 and also inclines downwardly from one parallel wall 29 to the other parallel wall 29, that is, from the parallel wall 29 which is nearest to the card analyzing mechanism to the other parallel wall 29 which is remote from such card analyzing mechanism. Each of such floor members 33 is provided with a recess 34 shown as curved, at the free end of such floor which is at the open end of the compartment. This recess 34 is provided to permit the operator to easily grasp the pack of cards that may have collected in such compartment in order to remove the same.

Each upper compartment 31 is divided from a lower compartment 32 by means of a floor member 35 having a similar compound angular inclination but extending downwardly from a partition 36 arranged parallel to the parallel wall 29 of each tier nearest from the card analyzing mechanism and forming between such parallel wall 29 and partition 36 the passage 37 through which the cards to be conveyed to the lower compartment are passed. The floor member 35 is provided with a recess 38 similar to the recess 34 and for the same purpose.

Each of the upper compartments 31 is provided with a curved guard 39 which is the upward continuation of the partition 36 and in conformation first rounds outwardly toward the card analyzing mechanism and then droops over so that its free end extends into the upper compartment 31. At the other side of the compartment 31, that is, the side nearest to the card analyzing mechanism, the upper end of the parallel wall 29 inclines toward the card analyzing mechanism and has at its upper end a curved guard 40 one free end of which curves over into the compartment 31 and the body portion of which extends substantially perpendicular as at 41 and then inclines away from the card analyzing mechanism in an arc as at 42. Thus the entrance to an upper compartment is constricted and is substantially protected from the outward bounding of a card that has been discharged into such compartment 31. The inclination at the upper end of a parallel wall 29 forms with the rearward curved portion of a guard 39 an outwardly flaring mouth for the passage 37. At the lower end of the passage 37 and forming with the floor member 35 an inwardly directed chute to the lower compartment 32, there is provided a deflector 43 preferably curved as shown whereby the card discharged into the passage 37 will strike such deflector and be deflected into the compartment 32 without flipping over.

Each of the upper compartments 31 is provided with two revolving rolls 44 disposed on stub shafts 45 parallel to one another and in a plane substantially horizontal, the stub shafts being each fixed to a partition 36 and a parallel wall 29, and having loosely mounted thereon a collar 46 on which is fixed a roll 44. These rolls 44 are of particular conformation illustrated in section in Fig. 6, each having a cone-shaped body portion 47 with a disk portion 48 at the narrow end of such cone-shaped body portion extending outwardly from such narrow portion and a pulley conformation 49 adjacent to the disk portion 48, the disk portion 48 separating such pulley conformation 49 from the cone-shaped body portion 47. The disk portion 48 is provided with a cushion member or leather covering 50 on the surfaces thereof which face the cone-shaped body portion 47. As shown in Fig. 5, the pulley conformation 49 of the roll 44 which is nearest the end wall 30 has a larger diameter than the pulley conformation 49 of the other roll 44. This is for the purpose of revolving the latter roll 44 at a faster rate of speed than the former. The cushion members 50 are provided to protect the cards and disks from injury due to the impact of the cards with the disks when being discharged onto such rolls.

Each of the lower compartments 32 is provided with two rolls 50 similar to the

rolls 44 one of which rolls 50, the one remote from the end wall 30 is mounted on the shaft 51 which is common to all the rolls of the lower compartments 32 which are remote 5 from end wall 30, this shaft 51 extending through the parallel walls 29. On such shaft 51 between each two adjacent parallel walls 29 is rotatably mounted a sleeve 52 on which a roll 50 is fixed, such roll 50 having 10 a conformation similar to the rolls 44, that is, a cone-shaped body portion 53, at the constricted end of which is disposed a disk member 54 and a pulley conformation 55 adjacent to such disk member 54. The 15 other roll 50 of a lower compartment is mounted on a shaft 56 which is the drive shaft for the cone-shaped roll system. These latter rolls 50 having a similar cone-shaped body portion 57, disk member 58 and pulley 20 conformation 59 which are fixed to the drive shaft 56 by means of a pin 60 (Fig. 7). The disk members 54 and 58 of the rolls 50 are provided with a cover such as felt or leather 61 similar to the covering 50' of the 25 rolls 44. The rolls 50 adjacent to the end wall 30 are provided with pulley conformations of a greater diameter than the pulley conformations of the other rolls 50 similar to the rolls 44 so that the rolls 50 nearer 30 the open end of the lower compartments 32 may be revolved at a faster rate of speed.

The shaft 56 extends through all the parallel walls 29 being supported thereby and has one of its ends carried by a bracket 35 62, the free end of such shaft 56 extending through the bracket 62 and being provided with a bevel gear 63 in mesh with a bevel gear 64 at the lower end of a shaft 65 which is rotatably supported in a bearing 66 and 40 is operatively connected at its upper end with the main shaft 19, motion being thus transmitted to the shaft 56 by the shaft 19. All of the rolls 50 mounted on the shaft 56 are fixed to rotate with such shaft 56, and 45 they in turn transmit rotation to the other rolls 44 and 50. The rolls of each single tier are connected by a single belt to be driven together, each floor member 35 being provided with recesses 61' (Fig. 3) 50 through which a belt 68 passes, the pulley conformations of the rolls 50 and rolls 44 of each tier being disposed substantially in a single plane so that the belt 68 may conveniently be passed around all four pulley 55 conformations. From the foregoing, it is obvious that the rolls 44 and 50 nearer the open ends of their respective compartments, due to the lesser diameter of their pulley conformations compared to the diameter of 60 the pulley conformations of the other rolls will be rotated at a faster rate of speed.

The rolls 44 and 50 as shown in Fig. 2 have the broader ends of their cone-shaped bodies nearest the card analyzing mechanism so that the inclination of the cones

will be in the same direction as the inclination of the floor members 35 and 33.

At the open end of each compartment, both upper and lower, and fixed to the parallel wall 29 remote from the analyzing card 70 mechanism, there is formed a stub shaft on which is pivotally mounted a metal strip 67 extending downwardly therefrom, the stub shaft being preferably disposed near the upper end of a compartment and the strip 75 67 extending down beyond the floor member of the compartment to which it is connected. The metal strip 67 is spring pressed so that its lower end normally rests against a floor member and will serve as a stop for the 80 cards being discharged into a compartment and on the other hand will be sufficiently resilient so that when the cards of another compartment are desired to be removed, the strip will be pressed outwardly to facilitate 85 such removal.

The operation of the device is as follows: The rolls 44 and 50 will be continuously operated while analyzing takes place in the analyzing mechanism 22, the arrangement 90 being such that when a card has been analyzed and a deflector 26 set, the card will be advanced to such deflector, deflected by such deflector into contact either with the guard 40 of an upper compartment and prevented from bounding back by the curved 95 portions of the guards 39 and 40 and thereupon dropped onto the rolls 44 by the rotation of which it will be discharged onto the floor 35 and by its momentum carried into 100 contact with the metal strip 67; or else deflected by a deflector into a passage 37 from which it will strike the deflector 43, be thereby deflected onto the rolls 50 by the rotation of which it will be discharged onto the 105 floor 33 and by its momentum carried into contact with a metal strip 67.

By inclining the floor members 35 and 33 at the double angle described, the motion of the cards will be enhanced so that the 110 cards will with facility assume their proper final position. The inclining of the rolls 44 and 50 corresponds to the inclinations of the floor members and thus will deflect the cards to the proper angle before they arrive on the 115 floor members. The rolls obviously will rotate in a direction to advance the cards toward the open ends of their respective compartments. Each card when discharged into a compartment will drop onto both rolls of 120 a compartment, and thus by the difference in speed of the two rolls, the card will be simultaneously subjected to different rates of speed, and thereby the liability of a card remaining at rest on such rolls is greatly 125 minimized, if not entirely annihilated. Furthermore, if the card has acquired a certain momentum due to the rotation of the rolls, the greatest speed of the roll nearer the open end of a compartment will, when the card 130

has left the roll nearer the end wall 30 and rests solely on the roll nearer the open end, be effective to increase the speed of the card and thereby insure its passage to its proper 5 destination.

With the present arrangement, the cards are placed in the hopper 12 faced downward, and as shown in the diagram of Fig. 8, each card as it is fed into the sorting mechanism 10 22 discharged therefrom and fed into a compartment 30 or 31 will through this entire operation face downward so that the pack of cards collected in any one of the compartments will be in the order in which 15 they were arranged in the hopper 12.

It is obvious that various changes and modifications may be made to the details of construction without departing from the general spirit of the invention.

20 I claim:

1. In combination with card feeding means, of receiving means into which the cards are fed by such feeding means, means in said receiving means for properly directing and positioning the cards as they are fed into the same, floor members in said receiving means on which the collected cards rest, said floor members being inclined at a compound angle, that is, downward toward one 25 end and also from one side downward to the other so as to facilitate the movement of the cards into their final position.

2. In combination with card feeding means, of receiving means into which the cards are fed by such feeding means, and revolving rolls in said receiving means for properly directing and positioning the cards as they are fed into the same.

3. In combination with feeding means, 40 of receiving means for receiving the cards discharged by such feeding means, and a plurality of feed rolls in said receiving means for properly directing and positioning the cards as they are fed into the same, the last roll of said feed rolls in time of engaging the cards discharged in such receiving means having a comparatively faster rate of speed so as to increase the movement of the cards in order to properly hurl 45 them to their final position.

4. In combination with card feeding means, of receiving means for receiving the cards discharged by such feeding means, and a plurality of feed rolls in said receiving 55 means for properly directing and positioning the cards as they are fed into the same, floor members in said receiving means on which the collected cards rest, said floor members being inclined at a compound angle, that is, downward toward one end and also one side downward to the other side so as to facilitate the movement of the cards into their final position, said feed rolls having cone-shaped body portions by means of 60 which the cards are deflected to the proper 65

inclination before striking the floor members.

5. In combination with feeding means, of receiving means for receiving the cards discharged by such feeding means, and a plurality of feed rolls in said receiving means for properly directing and positioning the cards as they are fed into the safe, floor members in said receiving means on which the collected cards rest, said floor members being inclined 70 at a compound angle, that is, downward toward one end and also one side downward to the other side so as to facilitate the movement of the cards into their final position, said feed rolls each having a cone-shaped body 75 portion, a pulley conformation and a disk between the narrow end of the cone-shaped body portion and said pulley conformation to prevent the cards coming into contact with the pulley conformation, the cone-shaped body portion of the feed rolls deflecting the cards to the proper inclination 80 before they strike the floor members.

6. In combination with card feeding means, of receiving means for receiving the cards discharged by such feeding means, means for properly directing and positioning the cards as they are fed into the same, floor members in said receiving means on which the collected cards rest, said receiving means being open at one end through which the collected cards may be removed and a resilient stop disposed at the open end of a receiving means and obstructing the removal of cards therethrough against 90 which stop the cards are fed by said directing and positioning means, said resilient stop being sufficiently resilient to permit its displacement and thereupon removal of the 95 cards from such receiving means.

7. In combination with card feeding means, of receiving means for receiving the cards fed by such feeding means, feed rolls for properly directing and positioning the cards as they are fed into the same, floor members in said receiving means on which the collected cards rest, said receiving means being open at one end through which the collected cards may be removed, and a resilient stop disposed at the open end of a 100 receiving means and obstructing the removal of cards therethrough against which stop the cards are fed by said directing and positioning means, said resilient stop being sufficiently resilient to permit its displacement and thereupon removal of the cards' 105 from such receiving means.

8. In combination with card feeding means, of a plurality of tiers of compartments disposed one adjacent to the other 110 into which the cards are discharged by said card feeding means, each tier having two compartments one above the other, there being a passage alongside of the upper compartment to permit the passage of cards 115 120 125 130

therethrough into a lower compartment, two rolls in each compartment, a connecting means for connecting the four rolls of a single tier to operate together, a common 5 drive shaft passing through all of the tiers on which one of the rolls of a tier are fixed so that the drive shaft will transmit rotation to all of the rolls, said rolls being positioned in a compartment to receive the cards 10 discharged into such compartment and hurl them to their proper final position.

9. In combination with card feeding means of receiving means for receiving the cards discharged by such feeding means, and a 15 plurality of feed rolls in said receiving means for properly directing and positioning the cards as they are fed into the same, floor members in said receiving means on which the collected cards rest, said floor 20 members being inclined at a compound angle, that is, downward toward one end and also one side downward to the other side so as to facilitate the movement of the cards 25 into their final position, said feed rolls each having a cone-shaped body portion, a pulley conformation and a disk between the narrow end of the cone-shaped body portion and said pulley conformation to prevent the cards coming into contact with the pulley con- 30 formation, a cushion member on the surface of said disk facing said cone-shaped body portion against which the cards may strike when being discharged onto such roll, the cone-shaped body portion of the feed rolls 35 deflecting the cards to the proper inclination before they strike the floor members.

10. In a device of the character described, the combination of a plurality of tiers of compartments arranged side-by-side and 40 each comprising two compartments each having an entrance; a guide means co-operating with each entrance; means in the compartments for properly directing and positioning the cards after they leave the guide 45 means; and a floor member in each compartment and inclined toward a side and an end thereof.

11. In a device of the character described, the combination of a compartment into 50 which cards are fed, said compartment having an open end; and a floor member in said compartment and inclined toward said end and one side, said floor member being provided with a recess at the edge next to said 55 end.

12. In a device of the character described, the combination of a compartment into 60 which cards are fed, said compartment having an open end; a floor member in said compartment and inclined toward said end and one side; and a yielding positioning means at the side of said opening.

13. In a device of the character described, the combination of a compartment into 65 which cards are fed, said compartment hav-

ing an open end; a floor member in said compartment and inclined toward said end and one side; and a positioning blade at the side of said opening.

14. In a device of the character described, 70 the combination of a compartment in which cards may be piled; means for feeding cards into the compartment; and a pair of revolving cone-shaped rolls for positioning and directing the cards before they reach the pile. 75

15. In a device of the character described, the combination of a compartment in which cards may be piled; means for feeding cards into the compartment; and a pair of flanged revolving cones for positioning and directing the cards before they reach the pile. 80

16. In combination with card feeding means, of a plurality of compartments into which the cards are fed by said feeding means, said compartments being permanently open at one end sufficiently to permit the removal of the cards collected therein, and floor members in said compartments on which the collected cards rest, there being a recess at the edge of each floor member at 90 the open side of a compartment to permit grasping the pile of cards when it is desired to remove them and removing them while so held.

17. In combination with card feeding 95 means, of a plurality of compartments into which the cards are fed by said feeding means, means in said compartments for properly directing and positioning the cards as they are fed into the same, said compartments being open at one end to permit the removal of the cards collected therein, and floor members in said compartments on which the collected cards rest, said floor members being inclined at a compound 105 angle, that is, downward toward the open ends and also downward from the sides of the compartments nearer the feeding means. to the other sides of the compartments in which they are located so as to facilitate 110 the movement of the cards into their final position.

18. In combination with card feeding means, of a plurality of tiers of compartments disposed one adjacent to the other, 115 each tier having two compartments, guide means, one positioned at the entrance of each compartment, and floor members in said compartments on which the collected cards rest, said floor members being inclined at a compound angle, that is, downward toward the open ends and also downward from the sides of the compartments nearer the analyzing mechanism to the other sides of the compartments in which they are 125 located so as to facilitate the movement of the cards into their final position.

19. In combination with card feeding means, of receiving means for receiving the cards discharged by such feeding means, of 125

- a plurality of feed rolls in said receiving means for properly directing and positioning the cards as they are fed into the same, and floor members in said receiving means on which the collected cards rest, said feed rolls having cone-shaped body portions by means of which the cards are deflected to the proper inclination before striking the floor members.
19. 20. In combination with card feeding means, of receiving means for receiving the cards fed by such feeding means, a plurality of feed rolls in said receiving means for properly directing and positioning the cards as they are fed into the same, floor members in said receiving means on which the collected cards rest, said feed rolls each having a cone-shaped body portion, a pulley conformation and a disk between the narrow end of the cone-shaped body portion and said pulley conformation to prevent the cards coming into contact with the pulley conformation, the cone-shaped body portion of the feed rolls deflecting the cards to the proper inclination before they strike the floor members.
21. In combination with card feeding means, of receiving means for receiving the cards discharged by such feeding means, a plurality of feed rolls in said receiving means for properly directing and positioning the cards as they are fed into the same,
- 20 end of the cone-shaped body portion and said pulley conformation to prevent the cards coming into contact with the pulley conformation, the cone-shaped body portion of the feed rolls deflecting the cards to the proper inclination before they strike the floor members.
- 25

and floor members in said receiving means on which the collected cards rest, said feed rolls each having a cone-shaped body portion, a pulley conformation and a disk between the narrow end of the cone-shaped body portion and said pulley conformation to prevent the cards coming into contact with the pulley conformation, a cushion member on the surface of said disk facing said cone-shaped body portion against which the cards may strike when being discharged onto such roll, the cone-shaped body portion of the feed rolls deflecting the cards to the proper inclination before they strike the floor members.

22. In combination with card feeding means, of receiving means, into which the cards are fed by such feeding means, and revoluble means for properly directing and positioning the cards as they are fed into the receiving means.

23. In combination with card feeding means, of receiving means into which the cards are fed by such feeding means, and conical deflectors in said receiving means for properly directing and positioning the cards as they are fed into the receiving means.

JAMES POWERS.
